UNITED STATES PATENT OFFICE

128,166

DESIGN FOR A CLOCK OR SIMILAR ARTICLE

Kate Lerman, Chicago, Ill.

Application May 17, 1941, Serial No. 100,994

Term of patent 7 years

To all whom it may concern:

Be it known that I, Kate Lerman, a citizen of the United States, residing at Chicago, in the county of Cook and State of Illinois, have invented a new, original, and ornamental Design for a Clock or Similar Article, of which the following is a specification, reference being made to the accompanying drawing, forming a part thereof, in which

Fig. 1 is a front elevational view of a clock embodying my new design;

Fig. 2 is a side elevational view thereof as seen from the left in Fig. 1; and

Fig. 3 is a side elevational view of the same as seen from the right in Fig. 1.

I claim:

The ornamental design for a clock or similar article, substantially as shown.

KATE LERMAN.
